Primary Examiner — T Chase Nelson*Assistant Examiner* — Laura H Yu(74) Attorney, Agent, or Firm — Banner & Witcoff, Ltd.(57) CLAIM

The ornamental design for a shoe, as shown and described.

DESCRIPTION

FIG. 1 is a photographic side view of a shoe showing our new design; and,

FIG. 2 is an enlarged photographic side view of the claimed region as shown in FIG. 1 with disclaimed environment removed for clarity purposes.

The grey faded portions in FIG. 1 are for the purpose of illustrating environment and form no part of the claimed design. The five broken lines surrounding disclaimed laces seen near the top in FIG. 1, but removed for clarity in FIG. 2, form no part of the claimed design. The five broken line circles in FIG. 2 represent eyelets which form no part of the claimed design. The broken line immediately adjacent to the bottom of the claimed photographic area represent the bounds of the claimed design and form no part thereof.
